United States Patent

Des. 241,199
Patented Aug. 31, 1976

241,199

COMBINED SOAP DISH AND MOUNTING BRACKET THEREFOR

Milton Halsted, Long Beach, Ivan A. McIntyre, Westminster, David Y. Muramatsu, Costa Mesa, and James P. Sullivan, Tustin, Calif., assignors to Chicago Specialty Manufacturing Company, Skokie, Ill.

Filed June 3, 1975, Ser. No. 583,511

Term of patent 14 years

Int. Cl. D23—02

U.S. Cl. D6—90

FIG. 1.

FIG. 2.

FIG. 3.

FIG. 4.

FIG. 1 is a perspective view of a combined soap dish and mounting bracket therefor, showing our new design.

FIG. 2 is a front elevational view.

FIG. 3 is a side elevational view, the side opposite being a mirror image thereof.

FIG. 4 is a bottom plan view.

We claim:

The ornamental design for a combined soap dish and mounting bracket therefor, as shown and described.
